UNITED STATES PATENT OFFICE.

ALBERT E. KEPPLER, OF PHILADELPHIA, PENNSYLVANIA, ASSIGNOR TO BROWN & BAILEY COMPANY, A CORPORATION OF PENNSYLVANIA.

DISPLAY BOX.

Application filed November 27, 1925. Serial No. 71,514.

My invention relates to display boxes, a principal object thereof being to provide a foldable box having means whereby the box may be positioned so as to display the contents in an attractive and advantageous manner, the box, to this end, embodying a unitary hinged portion or section adapted when in one position to form a rest or support for the main body of the box and its contents to hold the box in inclined display position.

A further object of my invention is to provide a box of the character aforesaid which may be constructed from a unitary blank of suitable material such as cardboard, the blank being cut out by a suitable die and the different parts thereof then folded into proper relation to form the completed box.

A still further object of the invention is to provide a foldable display box, integrally formed and adapted to be supported in an inclined position, which may be shipped flat to the user thereby effecting economy in transportation and expense and which may be then assembled in box form by the user, filled with merchandise and shipped to retailers for display and sale purposes.

A still further object of my invention is to provide a foldable display box which will not be destroyed or mutilated by a single use and which may therefore be refilled and used repeatedly.

My invention further includes all of the other various objects and novel features of design, construction and arrangement hereinafter more definitely specified or described or which will be apparent from the accompanying drawings in which I have illustrated a preferred embodiment of my invention.

In the said drawings, in which the same numerals designate like parts in the different figures, Fig. 1 is a perspective view of the box in display position; Fig. 2 is a front end view of the box with the movable supporting section turned down to vertical position so as to show the bottom and interior thereof; Fig. 3 is a longitudinal section of the box with the supporting section turned up to closed position; Fig. 4 is a transverse section on line 4-4 in Fig. 3

looking in the direction of the arrows; Fig. 5 is a plan view of the blank before the same is folded up to form the box, the points at which the blank is cut entirely through being indicated in full lines and those at 55 which it is scored or weakened to facilitate the folding operation being indicated in dotted lines, and Fig. 6 is a perspective view on a reduced scale showing the box partially inserted in a tube as when preparing it 60 for shipment.

The blank is formed from cardboard or other suitable material by a die in the shape best shown in Fig. 5, 1 designating the bottom of the box, 2 and 3 the ends and 4 and 5 65 the sides thereof.

In forming up the box from the blank the ends 2 and 3 and sides 4 and 5 are first folded on the scored lines 6, 7, 8 and 9, respectively, into positions at right angles to 70 the bottom 1 to form the container; the strip forming a prolongation of the end 3 and composed of sections 10, 11, 12 is then folded at the scored lines 10', 11', 12' 75 around the sides 4 and 5 and the end 2, section 10 paralleling side 4, section 11 paralleling end 2 and section 12 paralleling side 5; the end 13 of section 12 which, like the section 10, is of substantially the length of sides 4 and 5, is then secured by a suitable 80 adhesive to the tab 14 which is folded at the scored line 14' against the side 5.

The portion of the blank which forms the supporting portion of the box is generally indicated by the letter A in Fig. 5 and this 85 is next folded to assembled position in the following manner: The whole of portion A is bent about the scored line 16 and as this bending progresses the securing members 17 and 18 which have been bent about the 90 scored lines 19 and 20 respectively to positions at right angles to the panels 21 are inserted between the side 5 and the section 12 and the side 4 and the section 10 respectively, the ears 22 and 23 with which the 95 portions 17 and 18 are provided being inserted respectively in slots 24 and 25 in the sides 4 and 5 and bent downward, thereby providing a firm but disengageable locking means, panel 21 being thus brought to and 100

secured in a position contacting with and parallel to the bottom 1.

To form the movable supporting section generally designated as B the panel 28 is then bent backwardly somewhat on line 28' and the members 26 and 27 which form the inclined support for the box when in display position are then folded up at right angles to the panel; these members 26 and 10 27 are formed with inclined edges 26', 27', which, when the box is arranged for display purposes, rest on the showcase, counter or other support whereby the box and its contents are held in a tilted or inclined position contributing to their efficient and attractive display. The wings 29 and 30 are next folded inwardly on the scored lines 31 and 32 respectively, and the outside end portion 33 is then folded up vertically against 20 the wings 29 and 30 on the line 34, the inner end portion 35 then folded down on line 36 against the inner faces of the wings and the narrow strip or tab 37 folded on line 38 to rest upon the panel 28 and engaged beneath the ear 39 with which the panel is provided so as to lock the tab in position. This completes the folding or assembling operation.

After the box has been thus folded up or 30 assembled it is ready to be filled with merchandise and for convenience in shipping may be slid endwise into a suitable tube 41 which may also be formed of cardboard or the like, the movable supporting section B being, of course, folded up against the tray or box proper during this operation as shown in Fig. 6.

When it is desired to place the box and its contents in display position, and assuming that it has been removed from the tube, the movable section of the support, generally designated as B and comprising the members or portions 26, 27, 28, 29, 30, 33, 35 and 37, is folded or turned on the scored 40 line 28' from the position shown in Figs. 3, 4 and 6 to the position shown in Fig. 1, being thus turned through an angle of substantially 180°, so as to bring the panel 28 into contact with panel 21 with the inclined edges 26', 27' in position to rest on the showcase or other supporting medium to hold the box in the desired inclined display position. Of course the supporting section B may be as readily turned in reverse direction so as to bring it up into closed position should it be desired to lay the box flat on the counter or showcase or to re-insert it in the tube.

While I have herein described with considerable particularity a preferred embodiment of my invention I do not thereby desire or intend to specifically limit myself to the precise details of construction and arrangement of parts to which I have referred as the same may be modified and

varied in minor particulars from the forms shown in the drawings and herein described, without departing from the spirit and scope of the invention as defined in the appended claims.

Having thus described my invention, I claim and desire to protect by Letters Patent of the United States:—

1. A box formed from a single blank of foldable material and comprising a bottom, 75 sides, and end members, one of the latter being prolonged so as to be foldable about the sides and the other end member, and a support for the box comprising hingedly connected sections, one of said sections comprising a panel and foldable side members attached thereto and adapted to be locked to the box sides and the other of said sections comprising a panel and side members having inclined edges, wing members foldably attached to the side members, end members attached to the panel, and a tab carried by one of said end members and operative to lock with a portion of the 80 panel.

2. A box formed from a single blank of foldable material and comprising a bottom, 95 sides, and end members, one of the latter being prolonged so as to be foldable about the sides and the other end member, and a support for the box comprising relatively 100 movable sections, one of said sections being in fixed relation with the body and having a panel and foldable side members locked to the box sides and the other of said sections comprising a panel having locking means, side members having inclined edges and an end extending transversely between the side members and comprising inner and outer portions, wing members disposed between said portions and attached to the side members, and means on the inner portion operative to engage said locking means.

3. A box formed from a single blank of foldable material and comprising a bottom, 110 sides, and end members, one of the latter being prolonged so as to be foldable about the sides and the other end member, and a support for the box comprising relatively 115 movable sections, one of said sections having a panel and side members provided with locking means operative to lock said side members to the sides of the box and the other of said sections comprising a panel having locking means, side members having inclined edges, end members attached to the panel, and means carried by the end members operative to engage said locking means.

4. A box formed from a single blank of 125 foldable material and comprising a bottom, sides, and end members, one of the latter being prolonged so as to be foldable about the sides and the other end member, and a support for the box comprising relatively 130 movable sections, one of said sections having

a panel and side members provided with locking means operative to lock said side members to the sides of the box and the other of said sections comprising a panel, 5 side members adapted to be folded at right angles to the panel and having inclined edges, end members attached to the panel

and also adapted to be folded at right angles to the panel and means for locking said side members and said end members in 10 said folded position.

In witness whereof, I have hereunto set my hand this 24th day of November, 1925.

ALBERT E. KEPPLER.
